UNITED STATES PATENT OFFICE.

NILS P. JONSSON, OF OMAHA, NEBRASKA.

DESIGN FOR A SHIELD FOR SASH-PULLEYS.

SPECIFICATION forming part of Design No. 29,233, dated August 16, 1898.

Application filed September 28, 1897. Serial No. 663,380. Term of patent 3¹ years.

To all whom it may concern:

Be it known that I, NILS P. JONSSON, a citizen of the United States, residing at Omaha, in the county of Douglas and State of Nebraska, have invented and produced a new and original Design for a Shield for Sash-Pulleys; and I do declare the following to be a full, clear, and exact description of the same, reference being had to the accompanying drawing, forming a part thereof.

In the accompanying drawing the figure represents the perspective view of my shield for sash-pulleys.

As shown in the drawing, the leading and material feature of my design consists of a base-plate A, provided with the elongated openings 1 1 at each end and the central

opening 4, which central opening is covered by the outwardly - extending semicircular hood 2, closed at the upper end 5, but opened 20 at the lower end to form the opening 3, as shown.

Having thus described my invention, what I claim as new, and desire to secure by United States Letters Patent, is—

The design for a shield for sash-pulleys, as here shown and described.

In testimony whereof I affix my signature in presence of two witnesses.

NILS P. JONSSON.

Witnesses:

GEO. W. SUES,
ANE M. ELKJER.
